SAFETY NIGHT LIGHT GLASS

Charles Lipari, Brooklyn, N. Y.

Application December 10, 1941, Serial No. 422,315

5 Claims. (Cl. 67—21)

This invention relates to new and useful improvements in a safety night light glass or candlestick.

Heretofore, in the construction of safety night light glasses or candlesticks it has been customary to position a slow burning, relatively thick candle within a glass cup. This construction has been found objectionable in that during the night, upon occasion, the heat of the candle has caused the glass to crack and break in pieces permitting the molten wax and burning wick to fall on the surface upon which the glass is resting, marring the surface and sometimes causing fire.

It is proposed to overcome this objection in this invention by embedding a metallic safety shield within the glass of the container in a manner to hold the container together in the event that the heat of the candle cracks the same, so as to prevent the glass from falling apart to hold the molten wax and burning wick from falling out of the glass.

It is proposed to characterize the metallic safety shield by a piece of woven wire mesh or a chain wire element directly molded into and embedded within the surface of the glass in a manner to hold the glass together when it cracks.

A modification of the invention proposes to characterize the metallic safety shield by a perforated sheet metal cup shaped element embedded within the glass container.

It is a further object of this invention to characterize the perforated sheet metal member by a pair of inter-engaged perforated sheet metal cups provided with alignable openings arranged to permit the passage of light and which are adapted to be disaligned to close the openings and prevent the passage of molten wax in the event the glass container breaks away from the sheet metal cups.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a safety night light glass or candlestick constructed according to this invention.

Fig. 2 is a side elevational view of Fig. 1.

Fig. 3 is a vertical sectional view of Fig. 2.

Fig. 4 is a view similar to Fig. 2 but illustrating a modification of the invention.

Fig. 5 is still another view similar to Fig. 2 but illustrating a still further modification of the invention.

Fig. 6 is a horizontal sectional view taken on the line 66 of Fig. 5.

Fig. 7 is a vertical sectional view of a safety night light glass constructed in accordance with a modification of this invention.

Fig. 8 is a partial horizontal sectional view taken on the line 88 of Fig. 7.

Fig. 9 is a view similar to Fig. 8 but illustrating a shifted position of the sheet metal cups.

Fig. 10 is a bottom plan view of Fig. 7.

The safety night light glass or candlestick, according to this invention, comprises an open top glass container 10 having a candle 11. The open top glass container is constructed so as to have a side wall 10^a connected at its bottom with a bottom wall 10^b. The candle is of the short stubby variety and has a central wick 12 which is adapted to be lit. The top of the candle 11 is disposed slightly beneath the open top of the glass 10 to prevent the molten wax from running over the top thereof and on to the surface upon which the night light is resting.

A metallic safety shield is embedded within the walls of the glass 10. This metallic safety shield comprises a piece of woven wire mesh material 13 molded directly into and embedded between the faces of the walls 10^a and 10^b of the glass 10. This wire mesh material 13 is provided for the purpose of connecting the areas of the glass 10 so as to prevent the glass from falling apart in the event the heat of the candle cracks the glass.

In the modification of the invention shown in Fig. 4 a safety night light glass is shown of a construction similar to that previously described except for a slightly different form of metallic safety shield. In this form of the invention the metallic safety shield comprises a chain wire element 13' which is embedded into the walls 10^a and 10^b of the glass 10. This metallic wire element 13' is a fine variety of wire which is generally known in the trade as chicken wire.

In this form of the invention shown in Figs. 5 and 6 the construction of the night light glass is characterized by still another type of metallic safety shield. In this form of the invention the safety shield comprises a perforated sheet metal member 13" embedded into the walls of the glass 10. This sheet metal member 13" is provided with a plurality of closely arranged comparatively large perforations through which rays of light from the candle 11 may readily pass.

In this form of the invention shown in Figs.

7-10 the construction of the night light glass is characterized by a glass 20 having a pair of inter-engaging cup shaped members 20^a and 20^b. The inner cup shaped member 20^a houses a candle 21 having a central wick 22.

A metallic safety shield is embedded within the side and bottom walls of the inter-engaged cup shaped members 20^a and 20^b and comprising a perforated sheet metal member 23 comprises a pair of inter-engaged perforated sheet metal cups 23^a and 23^b disposed between the adjacent faces of the cup shaped glass members 20^a and 20^b. The cup shaped sheet metal members 23^a and 23^b are provided with a plurality of aligned perforations and a means is provided for facilitating the movement of one of the sheet metal cups relative to the other for aligning and disaligning the perforations in these sheet metal cups. This means comprises a knob 24 extended from the sheet metal cup 23^a and disposed within a cut-out 25 formed in the bottom face of the outer glass cup 20^b. This knob 24 may be rotated for rotating the sheet metal cup 23^a relative to the sheet metal 23^b for aligning and disaligning the perforations. A pin 26 extends from the sheet metal cup 23^b and is disposed within a slot 27 formed in the sheet metal member 23^a for limiting rotation of the sheet metal cups to positions in which the perforations will be aligned or disaligned.

The manner for using this latter form of the invention is as follows: Normally, the sheet metal cups 23^a and 23^b are arranged in a rotative position relative to each other in which their perforations will be aligned to permit the passage of light from the candle 21. However, upon retiring it is desirable to rotate the knob 24 to similarly rotate the sheet metal cup 23^a relative to the sheet metal cup 23^b. This disaligns the perforations in the cups 23^a and 23^b, and in the event that the heat of the candle should crack the glass members 20^a and 20^b it will be impossible for the molten wax to pass through the disaligned perforations.

It is to be understood that this device may be used for any suitable purpose without any danger of fire. For example, this safety night light glass or candle stick may be placed in an infant's room without fear that the place may be set on fire by the breaking of the night light glass.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A safety night light glass or candlestick, comprising an open top glass container for a candle and having a side wall and a bottom wall, and a metallic safety shield embedded within said side

and bottom walls, comprising a pair of inter-engaged perforated sheet metal cups, having alignable perforations; and means for moving one of said cups relative to the other for aligning said 5 perforations and for moving said perforations out of alignment.

2. A safety night light glass or candlestick, comprising an open top glass container for a candle and having a side wall and a bottom wall, and 10 a metallic safety shield embedded within said side and bottom walls, comprising a pair of inter-engaged perforated sheet metal cups, having alignable perforations, and means for moving one of said cups relative to the other for aligning said 15 perforations and for moving said perforations out of alignment, said means comprising a knob extended from one of said sheet metal cups and disposed within an opening formed in the bottom of said glass.

3. A safety night light glass or candlestick, comprising an open top glass container for a candle and having a side wall and a bottom wall, and a metallic safety shield embedded within said side and bottom walls, comprising a pair of inter-engaged 20 perforated sheet metal cups, having alignable perforations, and means for moving one of said cups relative to the other for aligning said perforations and for moving said perforations out of alignment, said glass being constructed of 25 inter-engageable cup shaped members with said perforated sheet metal cups being disposed between said cup shaped members.

4. A safety night light glass or candlestick, comprising a glass container having an open top for receiving a candle, a pair of interengaged sheet metal cups embedded in the walls of said container and turnable relative to one another, said cups being formed with aligned perforations, and a knob mounted on one of said cups by which 35 it may be turned relative to the other cup for aligning and disaligning said perforations to control the passage of light through the walls of said container.

5. A safety night light glass or candlestick, comprising a glass container having an open top for receiving a candle, a pair of interengaged sheet metal cups embedded in the walls of said container and turnable relative to one another, said cups being formed with aligned perforations, 45 and a knob mounted on one of said cups by which it may be turned relative to the other cup for aligning and disaligning said perforations to control the passage of light through the walls of said container, said glass container being constructed of inter-engaged cup shaped members with said sheet metal cups being disposed between said cup shaped members, said outer cup shaped member having its top edge formed with an inwardly 50 extending lip engaging the top edges of said sheet metal cups and its bottom wall formed with a central opening in which said knob is disposed.

CHARLES LIPARI.
